CLAMP

Filed Nov. 16, 1925

UNITED STATES PATENT OFFICE.

JOHN B. BENSON, OF INDEPENDENCE, KANSAS.

CLAMP.

Application filed November 16, 1925. Serial No. 69,457.

The invention aims to provide a new and improved form of clamp so designed as to effectively hold the separate sections of newel posts and the like in assembled relation while drying of the glue, by which they are connected, takes place.

The device is simple and it is inexpensively constructed, possessing a number of novel and advantageous features hereinafter described and claimed and shown in the accompanying drawing.

Figure 1 is a side elevation showing the clamp applied to a newel post.

Figures 2 and 3 are horizontal sectional views as indicated by lines 2—2 and 3—3 of Fig. 1.

Figure 4 is a view similar to Fig. 3 but illustrating the application of the invention to a post having a different cross sectional shape.

In the drawing above briefly described which illustrate the preferred form of the invention, the numerals 5 designate a plurality of parallel, transversely angular metal bars, and 6 designates a similar bar, the latter being separately identified in view of the fact that the construction associated with it is different from that of the bars 5. Only one of the bars 6 is necessary but any desired number of the other bars may be used and they may be of any preferred length and width. These bars are adapted for engagement with a newel post or other structure to be constricted, and it will be seen from Figs. 2, 3 and 4 that they engage portions of the structure, spaced apart around the periphery of the latter. When this structure possesses corners having the same angularity as the transverse formation of the bars 5 and 6, the latter may be applied to such corners as shown in Figs. 1, 2 and 3, and it will be understood that the transverse angularity of said bars may be changed according to the work upon which the clamp is to be used. These bars may if desired be engaged with a post or the like which is hexagonal, octagonal, round or any other shape in cross section, as will be clear from Fig. 4, and if desired, pads or the like (not shown) may be interposed between the bars and the work to prevent the former from in any manner injuring the latter.

At any desired number of points, spaced apart longitudinally of the bars 5, these bars are provided on their outer sides with trans-

verse projections 7, the outer sides of these projections being formed with smooth-bottomed grooves 8 which are open-ended and extend transversely of the bars.

At points spaced apart along the bar 6, corresponding to the points at which the projections 7 are disposed on bars 5, are lugs 9. Each of these lugs is formed with a bore 10 transverse to the bar 6 and is also provided with a notch 11 at one side of said bore. Spanning this notch and passing through portions of the lug 9 at opposite sides thereof, is a removable pin 12 preferably having a threaded engagement 13 with said lug, so as to prevent accidental displacement.

Binding elements in the form of chains 14 are shown, links of said chains being receivable in the notches 11 and being of a size to receive the pin 12. Screw-threaded adjusting devices are connected with the chains 14 and pass through the bores 10. Each of these devices, in the construction shown, comprises a screw-threaded shank 15 suitably connected at 16 with the chain 14, said shank passing slidably through the bore 10 and being provided on its outer end with a hand wheel 17 whose hub has threaded engagement with the shank. Preferably, a washer 18 is interposed between this hub and the lug 9.

In using the invention, the bars 5 and 6 are applied to the newel post or other structure to be constricted, the chains 14 are passed around this structure and the bars 5, while the hand wheels 17 are loosened, and said chains are connected with the lugs 9, by means of pins 12. These chains, it will be observed, are slidably engaged with the smooth bottoms of the grooves 8, so that upon tightening of the hand wheels 17, the chains will slide in said grooves as they are tightened. The device serves to effectively hold the structure in assembled position and its primary use is for performing such a holding function, while glue with which sections of the structure are connected, is allowed to dry.

Excellent results are obtainable from the details disclosed and they are therefore preferably followed. However, within the scope of the invention as claimed, variations may be made. Moreover, changes in size and strength, in the number of the bars 5, in the number of constricting devices for these

bars, etc., may be made within the scope of the invention as claimed.

I claim:—

- 5 1. A clamp of the class described comprising a plurality of parallel transversely angular bars for engagement with a structure to be constricted, said bars having transverse enlargements on their outer sides spaced apart longitudinally of said bars,
- 10 10 the outer sides of said enlargements having smooth-bottomed grooves extending transversely of the bars, an additional transversely angular bar having longitudinally spaced lugs on its exterior, said lugs having a longitudinal bore extending transversely to the bar and having in one side a notch at right angles to said bore, removable pins carried by said lugs and spanning said notches, binding chains detachably and adjustably connected at one end to said pins and passing around through the grooves in said enlargements, screw threaded tightening shanks slidably engaged with the bores in said lugs and directly connected at their inner ends to the opposite ends of said chains, and hand wheels having threaded hubs engaged with the outer ends of shanks and bearing against the outer ends of said lugs, whereby the turning of said wheels in one direction will draw said shanks through said bores and tighten said chains.
- 15 2. A clamp of the class described comprising a plurality of parallel transversely angular bars for engagement with a structure to be constricted, said bars having transverse enlargements on their outer sides
- 20 23

spaced apart longitudinally of said bars, the outer sides of said enlargements having smooth-bottomed grooves extending transversely of the bars, an additional transversely angular bar having longitudinally spaced lugs on its exterior, said lugs having a longitudinal bore extending transversely to the bar and having in one side a notch at right angles to said bore, removable pins carried by said lugs and spanning said notches, binding chains detachably and adjustably connected at one end to said pins and passing around through the grooves in said enlargements, screw threaded tightening shanks slidably engaged with the bores in said lugs and directly connected at their inner ends to the opposite ends of said chains, and hand wheels having threaded hubs engaged with the outer ends of shanks and bearing against the outer ends of said lugs, whereby the turning of said wheels in one direction will draw said shanks through said bores and tighten said chains.

In testimony whereof I have hereunto affixed my signature.

JOHN B. BENSON.
